UNITED STATES PATENT OFFICE.

GOLLADAY LAKE, OF NEW YORK, N. Y.

DEVICE FOR FASTENING COVERS.

Application filed March 11, 1926. Serial No. 93,877.

This invention relates to a device for fastening a cover on its supporting surface and maintaining the same in a smooth unwrinkled condition, and for the purposes of illustration, the invention will be described as used in fastening a cover on an ironing board, but it will be understood that the device may be used for fastening covers on tables of all kinds, for fastening temporary covers on automobile seats and the like, or for stretching green pelts on their supporting surfaces or for other kindred purposes.

It is a primary object of the present invention to provide a device for securing the cover on its supporting surface in a smooth condition, by exerting a pulling action on the marginal edges of the cover in both transverse and longitudinal directions, the strain on the marginal edges of the cover being equally distributed throughout.

A further object is to provide such a device that is easily attached to and removed from the cover.

Still another object is to provide such a device that is substantially flat to enable the board and the like to rest uniformly and in a flat position on its supporting surface.

Still another object is to provide such a device that is simple and inexpensive to manufacture and one that can easily be adjusted to all sizes of covers.

Other advantages will appear from the description to follow taken in connection with the drawing in which—

Figure 1 is a rear elevation of an ironing board having a cover thereon with the improved fastening device attached thereto.

Figure 2 is an enlarged detail view of one embodiment of the invention, and Fig. 3 is a similar view of another modification.

Figure 4 is an enlarged detail view.

Figure 5 is a view of the preferred form of my improved device removed from the cover and showing how it looks when in extended position.

Figure 6 is a detail view of one of the gripping members used in the preferred form of the invention shown in Figure 5.

Referring to the drawing in detail, in Figure 1 is illustrated an ironing board 10 of wood, having the usual long edges and rounded corners, tapering from end to end.

Entirely covering one of the flat surfaces (not shown) of the board 10 is a cover 11 made of cloth of any suitable material. This cloth for the purpose of economy is only

sufficiently large to extend over the edges of the board and terminates in marginal edges or flaps 12 and 13. Heretofore great difficulty has been experienced in keeping the part of the cover 11 which covers the front or working side of the board 10 in a smooth unwrinkled condition.

The form of the invention illustrated in Figure 2 comprises an elongated narrow body portion 14 of elastic material. Formed integral with and at either end of said portion 14 are short arms 16, said arms 16 being positioned at an acute angle of the portion 14. Mounted at spaced intervals throughout the length of the body portion 14 are gripping members or clasps 17 consisting of a flat body portion 18 and a neck portion 19, with a slot 20 formed therein. Extending from said body portion 18 is a hinge member 21 and hinged to said hinge member 21 is a complementary hinge member 22, the hinge therebetween being shown diagrammatically at 23. The gripping members 17 are mounted on the body portion 14 by placing said portion 14 on the pricked surface of the hinge member 21 and then swinging the hinge member 22 over said portion 14.

Mounted on the end of said short arm 16 is a gripping member 25 substantially similar to the gripping members 17 but provided with an up-turned portion 26 upon the upper surface of which are formed lugs similar to the lugs 24 illustrated in Figure 4. Secured to said portion 26 by a hinge indicated at 27 is a flat body portion 28 also provided with lugs similar to the lugs 24. To mount this gripping member 25 on the short arm 16, said arm 16 is placed over the up-turned portion 26 and the body portion 28 is then swung over said arm 16.

In Figure 3 is illustrated another form of the invention comprising a body portion 14' having secured thereto a plurality of short cross arms 29, spaced at intervals, said arms 29 being sewed to the body portion 14' by means of the stitches 30. A gripping member 31 similar to the gripping members 17 is mounted on either end of said cross arms 29. Sewed to the ends of said body 14' at an acute angle thereto are short arms 32.

In Figures 5 and 6, the preferred form of the invention is illustrated. Figure 5 shows the improved device removed from the iron board cover. It comprises an elongated narrow body portion 14" formed of

elastic material but which may be made of any suitable material which is adapted to stretch. The ends of said body portion 14" are turned back to the point indicated at 33 thereby reinforcing said ends. Mounted detachably on either of said ends is a gripping or fastening member 34 comprising wire body sections 35 and 36 joined by an eyelet or loop 37, said sections 35 and 36 and eyelet 37 formed of a single piece of wire, the said eyelet being positioned medially of said wire. The body portion 35 terminates in a hook 38 provided with a sharp point, said hook 38 being adapted to engage the marginal edges 12 and 13 of the cloth cover 11. The flat body portion 36 is bent upon itself or formed with a turned back section 39 forming a loop and terminates in an upwardly bent portion or hook 40 also provided with a sharp point as is shown in Figure 6.

This portion 40 is positioned directly beneath and in alignment with the loop 37 and because of the flexibility of the wire material forming said gripping member 34, the portion 40 is adapted to be pushed through the eyelet 37. When the said gripping member 34 is in operative position the body portion 14" is positioned in the space indicated at 41 between the sections 39 and 36. In Figure 6, the broken lines indicated at 42 represent the position of the section 39 when in inoperative position. It will be noted from Figure 5 that when the gripping members 34 at the end of the body portion 14" are in position on the body portion 14", the sections 35 and 39 are disposed parallel with the edges of the body portion 14, while the body section 35 is disposed at an acute angle to the body portion 14", thereby being disposed at the same angle with reference to the body portion 14" as the arms 16 and 32.

From Figure 5 it will also be noted that the gripping members 34 are also mounted at spaced intervals along the body portion 14", but it will be noted that they are disposed in staggered relationship to each other, that is, every other gripping member 34 is mounted on the opposite side of the body portion 14" and not directly opposite each other.

In operation the gripping or fastening members 34 on the ends of the body portion 14" are first secured to the edges 13 of the cover 11 by catching the hook 38 in the cloth. It will be understood that the body portion 14" is not quite as long as the board 10 so that when the fastening members 34 are secured to the edges 13 of the cloth, the body portion 14" is elongated or stretched with a resulting pull on said edges 13 longitudinally of the board 10. The fastening members 34 are mounted along the body portion 14" and then secured to the marginal

edges 12 of the cloth by catching their hooks 38 in said marginal edges resulting in said marginal edges 12 being united by means of a zig-zag or cross stitch, the same as if said edges were stitched or sewed. By reason of this zig-zag or cross stitch tying of the edges 12 and 13 of the cloth 11, there is a radial pull, that is, a pull in all directions on the cloth 11 which tends to distribute the strains on said edges equally throughout and tends to keep the front portion of said cloth 11 in a smooth and tight condition.

In using the form shown in Figure 3, the gripping members 31 are secured to the edges 12 at points directly opposite each other but because of the elasticity of the cross arms 29 sufficient play is afforded to enable the said gripping members 31 to hold the cloth in a smooth condition and yet allow a slight lateral movement to prevent excessive strain at the points where the said gripping members 31 are secured to the edges 12. The short arms 32 are of course secured to the edges 13 of the cloth 11 in the same manner as the short arms 16.

In mounting the gripping member 34 on the body portion 14, the body section 39 is positioned below the portion 14 as viewed in Figure 5 by piercing the material of said body portion 14 at the point indicated at 43 and then forcing upwardly the portion 41 up through the material and the body portion 14 and through the eyelet 37 and then bending said body portion 41 laterally over the eyelet 37 to tie the sections together. The body section 35 is then bent laterally to an acute angle and the hooks 38 forced through the edges 13 of the cover 11. The gripping members mounted along the body portion 14 are mounted in the same way but the sections 35 thereof are parallel with the sections 36 and not bent at an angle thereto.

While I have described several embodiments of my invention, it will be understood that other variations may be resorted to without departing from the principle of the invention and I desire to be limited only by the state of the prior art and the appended claim.

I claim:

A device for holding a cover on an ironing board comprising an elongated body, fastening members removably mounted on said body, said fastening members each comprising a single length of wire formed with an eyelet medially of its ends, one end portion of said wire being bent upon itself to form a loop and having a hook for detachable engagement with said eyelet and the other end portion of said wire terminating in a hook.

In testimony that I claim the foregoing as my invention, I have signed my name hereto.

GOLLADAY LAKE.
